UNITED STATES PATENT OFFICE

ARTHUR HARDER, OF WARNEUMUNDE, GERMANY

DENTAL SPOON

Application filed March 23, 1928, Serial No. 264,161, and in Germany April 16, 1927.

My invention relates to a dental spoon for taking casts, impressions or prints of the upper jaw in which the material for taking the impression displaced by the penetration of the teeth is prevented from passing into the throat of the patient, by being collected in a special chamber and discharged from the mouth of the patient.

The spoons for taking casts ordinarily employed in the art of dentistry are open at the back or lightly arched and permit the material or compound used for taking the cast and displaced by the penetration of the teeth of the upper jaw to pass freely out at the back. 10 If a cast of the upper jaw is taken while the patient occupies a recumbent position the excess material is liable to penetrate into the throat of the patient and to cause irritations.

To overcome this drawback of the existing 20 dental spoons, a main spoon adapted to seal the throat has been enclosed from underneath by a second auxiliary spoon, a chamber being formed between the two spoons.

My invention consists substantially in providing an intermediate member or connection between the two spoons which does not rigidly fix the mutual position of the spoons, but permits a raising, lowering or lateral displacement of the lower spoon in relation to the upper. Preferably easily exchangeable 30 inspection windows are provided in the bottom of the lower spoon carrying the intermediate member. An extension of the spoon supporting the intermediate member is formed as discharge gutter and collecting receptacle for the excess compound.

An embodiment of my invention is illustrated in the accompanying drawing by way of example. In the drawing is:

40 Fig. 1, a longitudinal section,

Fig. 2, a plan,

Fig. 3, a cross-section through my improved dental spoon,

Fig. 4, a cross-section through the discharge

45 gutter,

Fig. 5, an inverted plan, and

Fig. 6 is an enlarged elevational detail view of the universal connecting means between the spoons.

50 Like parts are indicated by like letters of

reference throughout all the figures of the drawing.

Referring to the drawing it will be seen, that the upper or main spoon *a* does not differ from the usual spoons employed by dentists. The lower spoon *b* envelops the upper one from below and with it forms a space or compartment into which is received the excess material for taking the cast escaping from the upper spoon. Small quantities of this material remain in the space between the spoons, larger quantities are able to escape through the front gutter *d* to the end of the gutter formed as receptacle *e*. The gutter *d* and the receptacle *e* form part of the lower spoon in contrast with the known dental spoons, with a separate cavity for the reception of the displaced material for taking the cast.

The novel connection or combination of the two spoons according to my invention permits a slight change of the position of the lower spoon in relation to the upper during the process of taking the impression or cast. 70 For this purpose a joint *f* is provided between the two spoons, which permits the rear end of the lower spoon to be raised or lowered in order to attain a particularly effective seal towards the rear by forcing the rear end of the spoon *b* gently against the roof of the 75 mouth of the patient, while the upper spoon retains its firm hold within the teeth in the upper jaw. The capacity of the space or compartment between the two spoons may thus also be varied by changing the mutual 80 position of the spoons according to the quantity of the impression material to be discharged.

The strip *g* of rubber, guttapercha, caoutchouc or the like is intended to reduce the irritation when the rear end of the spoon *b* is pressed against the roof of the mouth and to assist in producing a good seal. Guttapercha strips as used for closing filled teeth may 90 preferably be employed for these packing strips *g*, which are then heated and pressed down upon the edge of the lower spoon. They 95 may easily be removed after having been used once and be replaced by a fresh one.

The easily exchangeable inspection win-

dows *h* of celluloid or a similar material provided in the bottom of the lower spoon *b* enable the process taking place in the spoon to be closely observed and also whether the packing strip *g* fits well and the impression material is properly discharged, so that, if required, the rear end of the spoon *b* may be raised without the patient altering his position in the dental chair.

10 The connection or combination of the upper spoon *a* with the lower spoon *b* may be effected by means of the joint or hinge *f* or through the agency of a plate *i* which closely adapts itself to the lower shape of the spoon *a* and is in its turn connected to the upper spoon *a* in an easily detachable manner, for instance by screws *k*, which may easily be removed for cleaning and sterilizing the spoons.

20 Various modifications and changes may be made without departing from the spirit and the scope of the invention, and I desire, therefore, that only such limitations shall be placed thereon as are imposed by the prior art.

25 I claim as my invention:

25 1. In a dental spoon for taking casts of the upper jaw, in combination, a main spoon adapted to produce a tight seal towards the throat, a spaced lower spoon adapted to enable 30 close the said main spoon from below, so that a space is left between said two spoons, and means to universally connect said spoons in such a manner that said lower spoon is movable toward and from said main spoon 35 and laterally thereof.

2. In a dental spoon for taking casts of the upper jaw, in combination, a main spoon adapted to produce a tight seal towards the throat, a spaced lower spoon adapted to enclose the said main spoon from below, so that a space is left between said two spoons, an intermediate member adapted to connect said spoons so that the lower is universally movable in relation to the upper, and easily detachable inspection windows in the bottom of said lower spoon supporting said intermediate member.

3. In a dental spoon for taking casts of the upper jaw, in combination, a main spoon adapted to produce a tight seal towards the throat, a spaced lower spoon adapted to enclose the said main spoon from below, so that a space is left between said two spoons, an intermediate member adapted to connect said spoons so that the lower is universally movable in relation to the upper, and an impression material discharge gutter terminating in a collecting receptacle forming an extension of said lower spoon.

66 In testimony whereof I have affixed my signature.

ARTHUR HARDER.
